CLAIM

The ornamental design for a payment device, as shown and described.

DESCRIPTION

FIG. 1 is a front isometric view of a payment device in accordance with the present design;

FIG. 2 is a front view thereof;

FIG. 3 is a back view thereof;

FIG. 4 is left side view thereof;

FIG. 5 is a right side view thereof;

FIG. 6 is a top view thereof; and,

FIG. 7 is a bottom view thereof.

The broken lines in the drawings depict parts of the payment device that form no part of the claimed design. The shading represents contour of the claimed design.
